A. T. REID

TOILET CASE

Filed Feb. 16, 1923

Inventor
Albert T. Reid,

By *B. D. McElwaine*

Attorney

UNITED STATES PATENT OFFICE.

ALBERT T. REID, OF LEAVENWORTH, KANSAS.

TOILET CASE.

Application filed February 16, 1923. Serial No. 619,469.

To all whom it may concern:

Be it known that I, ALBERT T. REID, a citizen of the United States, residing at Leavenworth, in the county of Leavenworth, 5 and State of Kansas, have invented certain new and useful Improvements in Toilet Cases, of which the following is a specification.

My invention relates to improvements in 10 toilet cases, ordinarily known as "vanity cases" for holding powder, rouge, or the like.

An important object of the invention is to provide a device of the above mentioned 15 character, which has the maximum volume for a given thickness.

A further object of the invention is to provide means whereby a single mirror is carried by one casing section, and automatically 20 moves to an open position, when the casing sections, containing the powder and rouge, are opened, the mirror assuming an operative position with respect to both casing sections.

25 A further object of the invention is to provide means for holding the mirror in the lowered position, until the opening casing section has been shifted to a selected position.

30 A further object of the invention is to provide a device of the above mentioned character, which is freely pivoted upon a bail, serving as a convenient support for the same.

35 A further object of the invention is to provide casing sections having their ends spherically curved, for stiffening the same, and providing the maximum holding capacity.

40 A further object of the invention is to provide a compact base which is spherically curved, to stiffen the same, and provide the maximum holding capacity.

45 A further object of the invention is to provide a compact base so constructed that it is extremely simple, and is held in place by frictional engagement, and may be readily removed from the casing.

50 Other objects and advantages of the invention will be apparent during the course of the following description.

In the accompanying drawings forming a part of this specification, and in which like numerals are employed to designate like parts throughout the same,

Figure 1 is a perspective view of a case embodying my invention,

Figure 2 is a similar view, with the casing sections open,

Figure 3 is a plan view of the same, and, 60

Figure 4 is a central vertical longitudinal sectional view through the same, the parts being closed.

In the drawings, wherein for the purpose of illustration is shown a preferred embodiment of my invention, the case is shown as formed of two coacting casing sections 5 and 6. The casing section 6 has its outer edge offset inwardly, forming an annular flange 7, of reduced diameter, which is inserted within the coacting casing section 5. The casing section 5 is hinged to the casing section 6 as shown at 8. Any suitable means may be employed to retain the casing sections 5 and 6 in the closed relation, and for the purpose of illustration, I have shown the flange 7 as provided with an outwardly bulging stud 9, to snap within an outwardly bulging socket 9', formed in the coacting casing section 5. 80

The numeral 10 designates a U-shaped bail or handle which is freely pivoted to the casing 5, at 11, so that the casing sections, when closed, may freely spin therein. The bail 10 is equipped with a swiveled eye 12, to which a chain or the like may be conveniently attached. 85

The numerals 13 and 14 designate rouge and powder compacts, which are mounted upon bases 15, which are identical. Each base is shown as circular, Figure 3, but of course it could be made in any other suitable shape, to correspond to the shape of the casing section. The compact base is preferably formed of metal, although other suitable material may be employed, and to render the same suitably stiff, I preferably spherically curve the same. This spherical curve also enables the same to fit snugly within the spherically curved end 5', of each 90 casing section. A further object in having the compact base spherically curved is that it provides the maximum holding capacity. A disadvantage heretofore encountered in connection with cases of this character, is 95 that no wholly satisfactory means has been provided for retaining the compacts in the casing sections. Attempts have heretofore been made to do this, but they are ordinarily complicated, and difficult to operate, particu-

100

110

larly with the gloves on the hand. In accordance with my invention, I contemplate equipping each of the compact bases 15 with friction elements or lugs 16, which extend radially beyond the periphery of the compact base, for a substantial distance, and are adapted to frictionally engage with the periphery of the casing section. As clearly shown in Figure 3, this affords a surrounding space 17, in which the point of a hair pin, or other implement, may be conveniently inserted, for removing the compact base.

The numeral 18 designates a mirror frame, which is hinged to the casing section 6, by means of a spring hinge 18'. This hinge 18' is preferably lowered within the casing section 6, so that its upper side is flush with the edge of the casing section. This spring hinge embodies a spring element or pintle, the ends 19 of which, engage with the casing section 16, and the frame of the mirror, as shown. The frame 18 holds a mirror 20 or other suitable reflector. This frame, and its mirror, are mounted within the casing section 6, below the edge of its periphery. When the casing section 5 is moved to the open position, with respect to the casing section 6, Figure 2, the mirror frame 18 will automatically swing to the open position, and be disposed at approximately an angle of 135° to the casing section 6. In this position, the mirror may be used in connection with both casing sections.

Means are provided to prevent the mirror frame 18 from moving upwardly, to any considerable extent, before the opening casing section has been shifted upwardly sufficiently, so that the mirror frame could not throw the puff in such casing section from the same. Such means preferably includes a catch or holding element 21, preferably rigidly secured to the periphery of the casing section 5, and projecting radially inwardly therefrom, to engage over the mirror frame 18.

As clearly shown in Figure 4, a rouge puff 13' is arranged between the rouge compact 13 and the mirror 20, and a powder puff 14' is disposed between the powder compact 14 and the mirror 20.

In use, the eye 12 may be suspended from a chain or the like, and the entire case may be freely spun within the bail 10. When it is desired to use the powder and rouge the casing section 5 carrying the bail 10 is arranged in the uppermost position, and the bail serves to indicate to the user which casing section is uppermost. The casing section 5 is then swung upwardly. As the casing section 5 rises, the holding element 21 moves upwardly with it, but remains in the path of travel of the free end of the mirror frame 18, whereby this mirror frame can-

not move upwardly until the casing section 5 has been shifted to a suitable upright position. This is advantageous, as otherwise, the mirror frame 18 being released prematurely, might throw the rouge puff from the casing section 15. Upon the continued outward movement of the casing section 5, the holding element 21 swings out of the path of travel of the mirror frame, and the spring hinge will then automatically swing the mirror frame to the outer upright position, which is preferably at an angle of about 135° with respect to the casing section 5. The mirror frame 18 being hinged within the casing section 6, is adapted, when swung to the outermost position, to engage with the periphery of this casing section, and hence be supported in the upright position.

I prefer to arrange the hinge 18' diametrically opposite the hinge 8, while the invention is not necessarily restricted to this arrangement.

It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, I claim:

1. In a toilet case, a casing section adapted for the reception of a rouge compact, a second casing section adapted for the reception of a powder compact and hinged to the first named casing section, one casing section being adapted to be folded into close relation to the other casing section for providing a closed case, a mirror adapted to be arranged within the closed case between the said compacts and a spring actuated hinge pivotally connecting the mirror with one casing section at a point spaced from the hinged connection between said casing sections, said spring actuated hinge serving to automatically shift the mirror to an open position when released, said mirror when in the open position being so located with respect to the opened casing sections that the same face of the mirror is adapted for use with both casing sections.

2. In a toilet case, a casing section adapted for the reception of a rouge compact, a second casing section adapted for the reception of a powder compact, a hinge connecting the casing sections whereby they may be shifted into close relation to each other for forming a closed case and may be shifted to an open position in substantially the same plane, a mirror having a single reflecting face, a hinge arranged within one casing section at a point spaced from the first named hinge and connecting the periphery of such casing section with

the mirror whereby the mirror may be swung outwardly to a position beyond the perpendicular with respect to its casing section and will engage with the periphery 5 of such casing section and be supported thereby against further outward movement, and a spring to automatically swing the mirror to the extreme outer position when released, said mirror when occupying the 10 outer position having its single reflecting surface adapted for use with both casing sections.

3. In a toilet case, a pair of casing sections, hinge means connecting the casing 15 sections, a mirror to be arranged within the casing sections when they are closed, a spring actuated hinge for pivotally connecting the mirror with one casing section at a point substantially diametrically 20 opposite to the hinge means, and means carried by the other casing section and disposed adjacent to the hinge means for preventing the complete opening movement of the mirror until the last named casing section has been shifted outwardly to a selected 25 position.

4. In a toilet case, a pair of casing sections, hinge means connecting the casing sections, a mirror to be arranged within the 30 casing sections when closed, a spring actuated hinge for pivotally connecting the mirror with one casing section, and means carried by the other casing section for engaging the mirror and controlling its outward 35 movement.

5. In a toilet case, a pair of casing sections, hinge means connecting the casing sections, a mirror to be arranged within the

casing sections, means connecting the mirror with one casing section and serving to automatically shift the mirror to an open position when the mirror is released, and a holding member secured to the other casing section and adapted to engage with the mirror for controlling its opening movement 45 of the mirror.

6. In a toilet case, a casing member having a cylindrical periphery and an outwardly bulging spherically curved end, a spherically curved compact carrying base 50 adapted for insertion within the casing member with its spherically curved portion engaging snugly with said spherically curved end, said spherically curved base having its material continuing in the form of radial lugs integral therewith and which are adapted to frictionally engage with the cylindrical periphery of the casing member, said lugs providing openings between the edge of the base and the periphery of the casing member for the insertion of an implement for the removal of said base.

7. In a toilet case, a casing member, a compact carrying base adapted to be mounted within the casing member, said base having its material projecting radially beyond its periphery providing lugs integral therewith, said lugs being adapted to frictionally engage the periphery of the casing member and form openings between such periphery and the periphery of the base whereby an implement may be inserted within such openings for the removal of the base.

In testimony whereof I affix my signature. 75
ALBERT T. REID.
